UNITED STATES PATENT OFFICE.

HUGH W. SANFORD, OF KNOXVILLE, TENNESSEE.

RAILWAY CAR.

Application filed May 13, 1921. Serial No. 469,213.

To all whom it may concern:

Be it known that I, HUGH W. SANFORD, a citizen of the United States, residing at Knoxville, in the county of Knox and State of Tennessee, have invented a new and useful Improvement in Railway Cars, of which the following is a specification, reference being had to the accompanying drawing.

My improvement relates particularly to 10 railway cars in which provision is made for dumping a load of loose material through the bottom of the car at a chosen point on a railway track.

The object of my improvement is to provide 15 a railway car of economical and durable construction and which is adapted to the automatic opening of the bottom for dumping and the subsequent automatic closing of the bottom preparatory to receiving a new load, and particularly to provide 20 a construction which will permit rearward movement of the car without damage to the structure when the bottom of the car has accidentally opened, and further to provide 25 a car which will carry a maximum load with a low construction, thus adapting the car to travel where there is low head room.

For a car of the same general type, reference 30 is made to my United States Patent, No. 1,268,390, granted June 4, 1918, for an improvement in railways.

In that patent there is disclosed a car having a plurality of hinged bottom doors, the door at the rear of the car having at its rear edge a tongue which is normally engaged by a latch mechanism supported on the end of the car and which may be released manually or automatically when the discharge point 40 on the track has been reached, such point being ordinarily a tipple whereon is provided a cam so positioned as to bear against the bottoms of the doors successively and push them upward into the closed position, during the forward movement of the car after the load in the car has been dumped.

In the present improvement, one door is substituted for the three doors of said patent, as will be hereinafter described.

50 In the accompanying drawings,

Fig. 1 is a section along the upright, middle, longitudinal plane of the car;

Fig. 2 is a transverse, upright section on the line, 2-2, of Fig. 1;

55 Fig. 3 is an upright longitudinal section

similar to Fig. 1, some parts being omitted, and the free end of the bottom door resting on the track surface.

Referring to said drawings, A, A are track rails. B, B are ordinary car wheels applied to the ends of the axles C, C, which extend transversely across the body of the car. D, D are side sills. E, E are end sills. F is the upper part of the car body.

G is a shaft extending across the car body horizontally and parallel to the inner face of one of the end sills and having its ends resting in the side sills.

H is the bottom door. This extends beneath the axles, C, C, and fills the space between the side sills. Its rear end extends close to the shaft, G, and is secured thereto by a hinge, H¹. At each side edge, said door has an upward-directed flange, H², which serves to stiffen the door and to allow the door to extend along the lower edges of the side sills. The door is long relative to the height of its hinge above the track surface, S.

A tongue, H⁴, is attached to the middle of 80 the free end edge of the door. Said latch is to be engaged by latch mechanism supported on the adjacent end of the car, as described in the above-mentioned patent.

Said latch mechanism comprises two 85 angle levers, I, hinged to the end of the car above at I¹ and each having a long arm extending horizontally outward far enough to be engaged by a stationary cam located beside the track for lifting said ends, as described in said patent.

The other arms of said levers are directed downward and each has a hook, I², adapted to extend beneath the tongue, H⁴, and support the latter when the door is in the raised 95 or closed position.

When the outer ends of the long arms of said levers are raised, the tongue, H⁴, is released from said hooks. Then the door is free to fall for the discharge of the load 100 in the car. When the door is again pressed upward, the tongue, H⁴, is forced upward between the hooks, I², the latter being forced sidewise until the tongue is above the hooks, whereupon the levers tilt, by reason of the 105 downward pressure of the long arms, until the hooks are again under said tongue. This operation is similar to the operation of the latch mechanism described in my said patent.

The movement of the car toward the un- 110

loading station is toward the left as viewed in Figs. 1 and 3, the hinge end of the door going forward.

Now attention is especially invited to three features: (1) the door is relatively long and between its ends it is curved downward so as to bring the greater part of the door as close to the track as feasible, whereby the car may be made low and yet carry a relatively large load, and whereby greater stability is given to the car, the load being close to the rails; (2) the length of the door adapts the door to remain nearly parallel to the track surface, S, if the latch mechanism accidentally releases the door so that the free end of the door goes downward and rests upon the track surface; (3) the free end of the door, the end which bears the tongue, H^4 , is curved upward as indicated by H^3 , so that said end of the door is made to resemble the forward end of a sled runner and is adapted to slide on the track surface when the car is moving backward and the door has accidentally been released and its latch end rests on the track surface.

The purpose of this sliding or sled action of the door is to prevent the end of the door from jamming into the track surface and wrecking the car structure and perhaps derailing the cars. The length of the door and the appropriate shaping of the latch end of the door contribute to forming a door adapted to such sled action. When a plurality of bottom doors are used, the inclination of the doors to the track surface is much increased, each door being short relative to the height of its hinge above the track surface.

The curvature of the part, H^3 , of the door may be increased by placing the latch mechanism higher than shown in the drawings.

As above stated, the flanges, H^2 placed at the edges of the door aid in stiffening the door. It will be understood that these flanges may be of any desired height and strength, and that similar stiffening flanges may extend along the middle of the door. Sagging of the door between its ends will be further resisted by the engagement of the tongue, H^4 , with the latch members, the free end of the tongue being bent downward to resemble a hook engaging the latch members to prevent horizontal movement.

It is also to be noted that when the long single door is accidentally released and rests on the track surface, on account of the low slant there will be a relatively small leakage of coal from the car.

I claim as my invention,

1. The combination of a car body, axles extending across and supporting said body, wheels carrying said axles, a relatively long bottom door extending under said axles and hinged by one end to one end of the car body and having its other end upturned and reaching to the other end of the car, and latch mechanism for engaging said upturned end of the door, substantially as described. 60

2. The combination of a car body, axles extending across and supporting said body, wheels carrying said axles, a relatively long bottom door curved downward between its ends and extending under said axles and hinged by one end to one end of the car body and having its other end upturned sled-fashion and reaching to the other end of the car, and latch mechanism for engaging said upturned end of the door, substantially as described. 75

3. The combination of a car body, axles extending across and supporting said body, wheels carrying said axles, a relatively long bottom door extending under said axles and hinged by one end to one end of the car body and having its other end upturned and reaching to the other end of the car, a tongue on said upturned end of the door, and latch mechanism for engaging said tongue, substantially as described. 80

4. The combination of a car body, a transverse shaft at one end of the car body, axles extending across and supporting said body, wheels carrying said axles, a relatively long bottom door extending under said axles and hinged by one end to one end of the car body and having its other end upturned and reaching to the other end of the car, and latch mechanism for engaging said upturned end of the door, substantially as described. 90

5. The combination of a car body, axles extending across and supporting said body, wheels carrying said axles, a relatively long bottom door extending under said axles and hinged by one end to one end of the car body and having its other end upturned and reaching to the other end of the car, a hook-form tongue on said upturned end of the door, and latch mechanism for engaging said tongue, substantially as described. 100

In testimony whereof I have signed my name, this second day of May, in the year one thousand nine hundred and twenty-one. 105

HUGH W. SANFORD.
